YARN PACKAGE LACING

Leo Lammert Brandsma, Arnhem, Netherlands,
assignor, by mesne assignments, to American
Enka Corporation, Wilmington, Del., a corpora-
tion of Delaware

Application September 9, 1932, Serial No. 632,408
In Germany September 18, 1931

4 Claims. (Cl. 242—1)

My invention relates to apparatus for lacing or binding artificial silk packages and similar yarn windings by means of threads or bands.

Artificial silk packages and other similar yarn windings are frequently laced or bound at several parts of their periphery to prevent the displacement of layers and the entanglement of threads, and the object of my invention is to provide an apparatus with the aid of which the lacing operation may be quickly and conveniently performed.

The apparatus comprises, essentially, a suitably supported plate so orificed that the threads or bands used for lacing the package may be freely looped about a package on the plate. The plate is desirably provided with a substantially central opening of substantially the diameter of the central opening in the package, and is surrounded in annular arrangement by a series of preferably annular orifices which lie beyond the outer periphery of the package and are each connected by a narrow slot with the central opening in the plate.

If it be desired to lace the package spiralled with a single thread or band instead of looping each of a plurality of bands once about the package, it is preferable to substitute for the radially extending slots connecting the central plate opening with the outside orifices, slots which if projected would pass the middle point of the central plate opening at substantially the same distance from such middle point.

The apparatus may be provided with a cover, preferably of substantially the depth of the package and having openings and orifices corresponding generally to those in the package supporting plate.

Several forms of the invention are illustrated in the accompanying drawing, in which Fig. 1 is an elevational view partly in section of one form of the invention; Fig. 2 is a plan view of a fragment of Fig. 1; Fig. 3 is an elevational view partly in section of another form of the invention and Fig. 4 is a corresponding fragmentary plan view; Fig. 5 is an elevational view of still another form of the invention and Fig. 6 is a corresponding view in section taken on line 6—6 of Figure 5.

Referring to the drawing and particularly to Figs. 1 and 2, the apparatus comprises a package supporting plate 1 secured to or formed integrally with columns 2 rising from a suitably anchored base plate 3. The plate 1 is provided with a central opening 4 connected by relatively narrow slots 6 with a series of orifices 5 arranged in a circle about the opening 4. The package

to be laced or bound is placed upright on the plate 1 concentrically to the central opening 4. As the diameter of the opening 4 is substantially equal to the diameter of the bore in the package, and as the orifices 5 are sufficiently spaced from the centre of the opening 4 to lie beyond the outer periphery of the package 7, the lacing threads or bands may be conveniently and quickly looped about the package through the slots 6. The opening 4 and orifices 5 are sufficiently large to enable the operator to work without hindrance and the slots 6 are at least equally as wide as the diameter or thickness of the thread or band used to lace the package 7.

The apparatus illustrated in Figs. 3 and 4 is much like that of Figs. 1 and 2 except that it is provided with a cover 8, hinged at 8^a to an upstanding flange 9 of the plate 1, and provided with a depending wall or arm 10 designed to rest, in closed position, on the plate 1. The length of flange 9 and wall 10 determines the distance the cover 8 is positioned from the plate 1. In this form of the invention the slots 6^a in the cover do not extend truly radially from the opening 4^a but are offset, as shown, in order that the lacing thread or band may be wound spirally about the yarn package 7.

In the modified form of Figs. 5 and 6, the supporting plate 1^a is carried by a standard 11 vertically adjustable in a bracket 12 and adapted to be held in adjusted position by a latch 17. Hinged to a foot 9 rising from the plate 1^a is a cover 8^b having a depending arm 10 to rest on the plate 1^a and limit the downward movement of the cover. Secured to the plate 1^a is a clamp 13 for holding the end of the lacing thread or band, and carried by the clamp is a cutter 14 to sever the thread. The plate 1^a has also secured thereto a knife 15 by means of which the knots in superimposed thread ends may be cut off. 16 denotes a receptacle or container for the ball of thread or band to be used for lacing.

If desired, the apparatus may be provided with suitable suction means, which it has been deemed unnecessary to show, for drawing off gases and vapors from the winding.

I claim:

1. A lacing apparatus for yarn packages, comprising a horizontally supported plate having an unobstructed central opening of substantially the diameter of the central opening in the yarn packages, a series of orifices located within said plate and surrounding said opening, and slots constituting the only openings to said orifices and

providing communication between said central opening and said orifices.

2. A lacing apparatus for yarn packages, comprising a horizontally supported plate having an unobstructed central opening of substantially the diameter of the central opening in the yarn package, a series of orifices located within said plate and surrounding said opening, and slots offset from the radial constituting the only openings to said orifices and providing communication between said central opening and said orifices.

3. A lacing apparatus for yarn packages, comprising a horizontally supported package supporting plate having an unobstructed central opening of substantially the diameter of the central opening in the yarn package, a series of orifices located within said plate and surrounding the central opening in the plate, and slots constituting the only openings to said orifices and providing communication between said opening in the plate and said orifices, an upstanding flange on the plate, a cover hinged to the said flange and having a central opening, orifices and slots

located in said cover, and means for spacing the cover from the plate.

4. A lacing apparatus for yarn packages, comprising a first plate horizontally supported for supporting the yarn package and having an unobstructed central opening of substantially the diameter of the central opening in the yarn package, a series of orifices located within said plate and surrounding the central opening in the plate, and slots constituting the only openings to said orifices and providing communication between said opening in the plate and said orifices, a second plate above the yarn package and having a central opening corresponding to the central opening in the first plate and a series of orifices located within said second plate surrounding said central opening, slots in said second plate constituting the only openings to the orifices in the second plate and providing communication between the central opening and orifices in the second plate, the slots in at least one of said plates being offset from the radial. 5 10 15 20
